UNITED STATES PATENT OFFICE.

ELMORE L. GOODLCE AND GEORGE E. PENISTON, OF KANSAS CITY, MISSOURI.

ILLUMINATED ADVERTISING DEVICE.

Application filed May 4, 1925. Serial No. 27,767.

The present invention relates to display or advertising appliances, and aims to provide a novel display cabinet of the illuminated type, and adapted to make a more effective or striking appearance when placed on exhibition in a display window or other place where the advertising function is desired to be carried out.

One of the principal objects in view is to provide an improved display apparatus in which novel means is used to produce a stereoscopic effect in the illumination of the display matter when the apparatus is put into operation. Accordingly, the present invention provides a cabinet wherein a display surface is arranged for a background of display material, in front of which is arranged a screen for carrying additional display material, the space between the screen and background being such that on illumination of both the screen and background surfaces a perspective effect is obtained as regards the appearance of the display material, with the matter on the screen standing out in a striking manner against the background.

It is further sought to provide a simple and practical apparatus for embodying the proposed improvements, and which will also permit of convenient change of the display material as often as desired.

With these general objects in view, the invention will now be described by reference to the accompanying drawing illustrating one form of apparatus which has been devised for embodying the improvements, after which those features and combinations deemed to be novel will be particularly set forth and claimed.

In the drawing—

Figure 1 is a front elevation illustrating a cabinet constructed in accordance with the present invention;

Figure 2 is an enlarged perspective view, with the cover member uplifted, and part of the cabinet broken away to disclose the interior; and

Figures 3 and 4 are views of the cabinet in vertical and horizontal section, respectively, on a still larger scale.

Referring now to the drawing in detail, this illustrates the invention as embodied in a cabinet 6, which is open at the front and the front edges thereof are formed with suitable molding 8, on the order of picture molding, so that the device presents the appearance of an art display cabinet. The top of

the cabinet is provided with a cover member 10, operating on hinges 12, to permit changing of the display material as presently to be explained. The front edge of the cover 10 is fitted with a reflector 14 carrying suitable electric lamps 16 for illuminating the display surfaces of the cabinet.

Inside the cabinet 6, and adjacent its rear corners are secured guide strips 18 for the purpose of forming guideways 20, for receiving the side edges of a placard 22 of cardboard or the like, carrying advertising or other display matter, such as the pictorial figures indicated at 24 and 26 in Figures 1 and 2. The strips 18 terminate slightly short of the top of the cabinet to facilitate the insertion of the placard 22 when fitting the same into the guideways or grooves 20.

At the front of the cabinet compartment are secured an upper cross-cleat 28 carrying a turnbutton 29, and a lower cross-cleat 30 provided with a retaining strip 31. Between these upper and lower cleats 28 and 30 is mounted a screen panel frame 32 carrying a sheet 34 of suitable transparent or translucent screen material, the frame 32 being fitted against the rear face of the molding 8, where it is held by the strip 31 at the bottom and the turnbutton 29 at the top.

On this screen material 34 is painted, or otherwise applied, such additional display material 35 as may be desired. In the present case this additional material is illustrated as the name "Aunt Sally's" intended to refer to the Figure 24 illustrated on the background formed by the surface of the placard 22.

With such an arrangement of the background surface and the screen surface carrying the two sets of display material, when the lamps 16 are turned on, both display surfaces are simultaneously illuminated, since the transparency of the screen 34 permits the light to shine through upon the placard 22. In addition, however, the effect of the screen is to tone down and soften the light which falls upon the background, so that the image which the observer receives of the display matter upon the background is similarly modified by the soft glow produced by the screen. In contrast to this is the brilliantly illuminated name 35 or other matter which the observer views direct on the screen, under the bright and unmodified glare of the lamps. The effect of the whole

display is thus of a stereoscopic character, as viewed in perspective, giving a much more natural and lifelike appearance than would be produced by the use of the single display surface, or without the action of the screen.

In this way, the principal item or feature of the display, in the present instance the name "Aunt Sally's", is made to stand out prominently, and so conspicuously as not to fail to be impressed upon the notice of the observer.

It is thus apparent that we have devised a novel and highly efficient device for fulfilling the objects of the invention. A much more ornamental and attractive display is obtained than by the means usually employed, and it is also obvious that the display matter can be changed on both the screen and the background as often as may be desired.

While we have illustrated and described what is now regarded as the preferred form of construction for embodying the invention, we desire to expressly reserve the right to

make such changes or modifications as may fairly fall within the scope of the appended claims:

What we claim is:

1. In a display device, the combination of an opaque background having a display surface, a translucent screen spaced a short distance in front of the background and provided with display matter, and illuminating means at the front of said screen in position for illuminating the display matter of said screen and for illuminating said background through the screen. 30

2. In a display device, the combination of a background having a display surface, a translucent screen spaced therefrom and provided with display matter and means arranged on the opposite side of the screen from the background for simultaneously illuminating both, whereby to produce a complete display of stereoscopic character. 40 45

In witness whereof we hereunto affix our signatures.

ELMORE L. GOODLOE.
GEO. E. PENISTON.
